UNITED STATES PATENT OFFICE.

GEORGE PIERCE TARVER, OF PENDLETON, OREGON.

BATTERY-CELL CONTAINER.

Application filed March 12, 1927. Serial No. 174,846.

The present invention is directed to improvements in containers for battery cells.

The primary object of the invention is to provide a container for this purpose so constructed that a plurality of dry or wet cells can be placed therein and compactly arranged, the container being formed from suitable sheet metal.

Another object of the invention is to provide a container of this nature constructed and arranged so that the same can be easily opened or closed to remove and replace cells as necessary, the closures for the containers having openings therein for the passage of the battery lead wires.

Another object of the invention is to provide a container of this kind which is so constructed that it can be conveniently carried from place to place, novel means being provided for securing the handles of the container in place.

In the accompanying drawings:

Figure 1 is a side elevation of the container.

Figure 2 is a vertical sectional view taken therethrough.

Figure 3 is a vertical sectional view through a modified form of the container.

Figure 4 is a similar view through another modified form of the container.

The container comprises a bottom plate 1 having a marginal shoulder 2 and horizontal flange 3, there being rods 4, preferably two in number, disposed in spaced relation, said rods having their lower ends soldered, or otherwise suitably secured to the bottom plate, as clearly shown in Figure 2 of the drawings.

The body 5 of the container comprises a wall which is oval in shape, but it will be of course understood that the body can be made any shape desired.

The top plate 6, like the bottom plate, is formed with a marginal shoulder 7 and a horizontal flange 8, said plate being provided with a pair of spaced perforations 9 through which the lead wires 10 of the battery cells 11 extend.

The top plate is further provided with openings 12 through which the upper ends of the rods 4 extend. In order that the container can be conveniently carried from place to place, the handle 13 is provided and has openings 14 in its ends for engage-

ment with the extended threaded ends of the rods 4, and upon which nuts 15 are engaged, said nuts not only serving to retain the handle engaged with the rods, but also serves to hold the body 5 with its upper and lower flanges 16 and 17 engaged tightly with the respective flanges of the top and bottom plates.

If desired, gaskets 18 of any suitable material may be placed between the flanges 8 and 16 and 3 and 17 to assure a tight moisture proof joint.

It will be observed upon reference to Figure 2 of the drawings, that the shoulders 2 and 7 snugly engage within the upper and lower ends of the body 5, thus firmly uniting the same with the top and bottom plates when the nuts are tightly clamped.

I have shown the container of a size to hold four cells, but it will be of course understood that they may be made in various sizes.

In the modified form of the invention, as shown in Figure 3 of the drawings, upper and lower body sections 19 and 20 are provided, having flanges 21 and 22, respectively, which when in assembled relationship constitutes a two-part container, and if desired a gasket 23 may be placed between said flanges.

The body section 19 is provided with perforations 24 for the passage of the lead wires 85 of the cells and is further provided with openings for the passage of the upper ends of the rods 26, the lower ends of which are fixed to the bottom of the body section 20, and like in the preferred form of the invention constitute means for holding the handle 27 and body sections 19 and 20 in assembled relationship.

In the modified form of the invention as shown in Figure 4 of the drawings, the 95 container comprises a body 28, there being rods 29 which have their lower ends secured to the bottom 30 thereof. A top plate 31 is provided and has openings 32 for the upper ends of the rods 29, there being a handle 100 33 secured by said rods, as in the preferred form of the invention. The top plate 31 is further provided with perforations 34 for the passage of the battery lead wires.

From the foregoing description, it will be 105 seen that I have provided a container so constructed that a plurality of cells can be conveniently stored therein and the con-

tainer conveniently moved from place to place. Further, it will be seen that a battery container has been provided which is simple in construction, durable and one which can be made at a very small cost.

Having thus described the invention, I claim:

A container for battery cells comprising a body having open upper and lower ends 10 provided with horizontal flanges, removable top and bottom plates having marginal vertical shoulders, said shoulders having horizontal flanges engaging the flanges of the body, when the shoulders are engaged

in the open ends thereof, the top plate having spaced openings therein, rods having their lower ends fixed to the bottom plate and their upper ends extended through said openings, a handle extended between the rods and having its ends detachably engaged with the extended ends of the rods, securing devices engaged on the extended ends of the rods and with the handle ends to hold the handle engaged with the rods and the flanges of the top and bottom plates engaged with the flanges of the body.

In testimony whereof I affix my signature.

GEORGE P. TARVER. [L. s.]
